UNITED STATES PATENT OFFICE.

MAX MIRKIN, OF NEW YORK, N. Y.

BATHTUB.

Application filed January 27, 1927. Serial No. 164,040.

This invention relates to collapsible bath tubs or the like and more particularly to small tubs, especially adapted for bathing children, and infants in particular, which 5 may be easily moved about from one place to another and collapsed and stowed away when not in use.

One of the objects of the present invention is to provide a simple and practical tub 10 of the above general character which may be inexpensively manufactured and assembled.

A further object is to provide a tub so constructed as to be free from the possibility 15 of collapsing when containing water in use.

A further object is to provide a tub of the above general character with a convenient form of adjusting means such as shown, for example, in my prior Patent, No. 1,584,240, 20 for permitting a telescopic temporary bottom to be raised and lowered at will.

A further object is to provide a tub of the above character having a movable dressing table adapted to be associated with the top 25 of the tub or either end upon which the infant may be placed after the bath.

Other objects will be in part obvious and in part hereinafter described in connection with the accompanying sheet of drawings 30 illustrating one of the various possible embodiments of the invention, and wherein similar parts are denoted by corresponding reference characters.

In these drawings—

35 Figs. 1 and 1^a together are perspective elevational views of the complete device with the dressing table detached.

Fig. 2 is a detail view of one form of locking means.

40 Fig. 3 is a detail view of one form of adjusting means.

Fig. 4 is a detail view of another form of toggle to prevent collapsing.

Fig. 5 is a detail of the table support.

45 Referring to Fig. 1, 10 indicates two main horizontally and longitudinally extending side bars which are preferably made of wood and to which a flexible collapsible tub is secured along its parallel longitudinal sides.

50 This tub is preferably made of rubberized cloth, altho of course other waterproof material or fabric may be used as desired. The ends of the tub are gathered at the corners or provided with stitched end walls and secured to these side bars 10 in any desired manner to form the complete rectangular

receptacle constituting the tub. The side bars are provided at or near their ends with downwardly diagonally extending legs 11 preferably made of metal so as to be relatively light in weight, yet amply strong to support the load. These legs cross each other at 12 where they are pivoted to permit relative turning movement when the tub is collapsed. A toggle 13 moves to extended 65 position when the tub is expanded to hold the tub against collapsing thereafter.

As a further precaution against this possibility, there is provided at each end transverse angle bar 14 (shown in detail in Fig. 70 2) each being pivoted at one end to the top of one of the legs 11 while the opposite end is slotted upwardly and horizontally as indicated at 15 (Fig. 2) thereby to coact with a headed stud 16 at the upper part of the 75 other leg 11. Thus it will be seen that when the rod or bar 14 is hooked over this stud and given a lateral movement, it is caused to move into locked position; when detached it, of course, swings downwardly to permit 80 collapsing of the tub.

This bar also carries a supporting means such, for example, as a supporting device 20 (Fig. 3) provided with one or more projecting buttons or studs 21 adapted to coact 85 with key hole openings 22 in a vertically extending rod 23. These devices may be permanently secured to the angle bars or clamped thereon as desired. This rod 23 is provided with a hooked handle 24 at the 90 top while its lower end is pivotally connected at one end to the base of the temporary bottom 25 as fully shown and described in my prior patent above referred to. The opposite end of this bottom 25 is provided 95 with a similar adjusting means whereby either or both ends of the temporary bottom may be raised or lowered vertically with the infant thereon as and when desired. Furthermore, the entire bottom 25 100 may be removed bodily by simply raising up on the hooks 24 which bring the pin-key hole supporting means 21—22 out of engagement.

It will also be noted that these end rods 105 14 are each provided at their top side with two longitudinal slots 26 which are adapted to be engaged by hooks 27 at one end of a temporary shelf or table 28. The opposite end of this shelf is provided with a depending supporting leg 30 hinged to the under side of the table as indicated at 31. When

the tub is to be collapsed, the hooks 27 are moved out of their slotted engagement with the rod 14. The table, which is preferably a canvas covered rectangular frame, is of a width to permit it to span the bars 10 when removed from its suggested position as shown in Fig. 1^a. Its end frame members are provided with slots 43 adapted to engage with telescoping or depressible pins 44 in the ends of side frame bars 10. Thus this cover may be moved from the position shown in Fig. 1^a attached to the side and moved upwardly and over the tub to serve as a dressing table. Under these conditions, the hooks 24 are disconnected and lower into the tub or removed as most convenient.

The tub, of course, is provided with a draining cock 32 at some convenient point on its under side and hose connection may be added if desired.

In Fig. 4 there is shown an alternative construction for the end bars 14. Here we have a toggle comprising two flat bars 35 pivoted at 36 to a supporting device 37 corresponding to the part 20 in Fig. 1. The two arms of the toggle may have a relatively longitudinal movement permitted by the slots 38, and locking rings 40 coact with the overlapping ends of the bars 35 to prevent collapsing. The opposite ends of the bars 35 are provided with attaching means 41 adapted to form means for attachment to the side bars 10 as by means of screws 42.

It will be seen from the above that the present invention comprises a simple and practical form of collapsible bath tub which may be inexpensively manufactured and assembled. The parts are so constructed and arranged as to positively prevent a collapsing of the tub when in use and the association of the temporary bottom and the lateral extending shelf and over-all sliding, dressing table makes the device particularly compact and convenient.

The invention is, therefore, well adapted to accomplish among others all of the objects and advantages herein set forth.

I claim—

1. In a collapsible bath tub of the character described, in combination, a main longitudinally extending supporting frame from which the tub is supported, cross legs at the ends of the tub for supporting the frame, a toggle holding said legs in expanded relation, and means parallel to said toggle forming ends for the frame and acting as a positive lock to prevent a collapse of the tub.

2. In a collapsible bath tub of the character described, in combination, a main longitudinally extending supporting frame from which the tub is supported, cross legs at the ends of the tub for supporting the frame, a toggle holding said legs in expanded rela-

tion, means parallel to said toggle forming ends for the frame and acting as a positive lock to prevent a collapse of the tub, a supporting device carried by each of said last means, and a temporary bottom for the tub adjustably suspended from said device.

3. In a collapsible tub of the character described, in combination, longitudinally extending side bars and transversely extending end bars constituting a rectangular frame from which the collapsible tub itself is suspended, said end bars each pivotally mounted at one end and having a separable locking engagement at their other ends, thereby to prevent a collapse of the tub, one of said bars having longitudinal slots intermediate its ends, and a temporary table having attaching means at one end cooperating with said slots and a supporting leg at the other end.

4. In a collapsible tub of the character described, in combination, longitudinally extending side bars and transversely extending end bars constituting a rectangular frame from which the collapsible tub itself is suspended, said end bars each pivotally mounted at one end and having a separable locking engagement at their other ends, thereby to prevent a collapse of the tub, one of said bars having longitudinal slots intermediate its ends, a temporary table having attaching means at one end cooperating with said slots and a supporting leg at the other end, and supporting devices carried by said transversely extending bars and projecting over the end edges of and into the tub adapted to support a temporary adjustable bottom within said tub.

5. In a collapsible tub of the character described, in combination, longitudinally extending side bars and transversely extending end bars constituting a rectangular frame from which the collapsible tub itself is suspended, said end bars each pivotally mounted at one end and having a separable locking engagement at their other ends, thereby to prevent a collapse of the tub, one of said bars having longitudinal slots intermediate its ends, a temporary table having attaching means at one end cooperating with said slots and a supporting leg at the other end, and supporting devices carried by said transversely extending bars and projecting over the end edges of and into the tub adapted to support a temporary adjustable bottom within said tub, said temporary bottom having upwardly extending hooked arms with openings adapted to adjustably engage the said supporting device.

Signed at New York, New York, this 25th day of January, 1927.

MAX MIRKIN.
